UNITED STATES PATENT OFFICE.

HANS SCHEIDEMANDEL, OF MUNICH, GERMANY.

DEVICE FOR ASSORTING OF MOLDINGS, FOR INSTANCE WOODEN BOARDS.

Application filed September 18, 1926, Serial No. 136,361, and in Germany September 14, 1925.

The invention relates to a device, by means of which moldings, as wooden boards for instance, may be assorted according to length, width or thickness and delivered automatically at defined places in accordance with their dimensions. The device in a modified form can also be used to convey moldings of any dimensions to defined places and deliver them there automatically.

The accompanying drawings illustrate the invention, as follows:

Fig. 1 shows a device with hopper-like box, which receives the moldings.

Fig. 2 shows a box with bottom-flap in closed position.

Fig. 3 shows a box with bottom-flap in opened position.

Fig. 4 shows a device with hopper-like box for delivering a molding of any size at a defined place.

According to Fig. 1 a plurality of suitably arranged hopper-like boxes is provided upon an endless band *a* running in the direction of the arrow. The walls *C* in front of the boxes have outlet-slots *d*, through which the revolving moldings *e* may pass. Above the endless band *a* cam arrangements *g₁*, *g₂*, *g₃* of different length are provided.

The operation of the device is the following: One molding always is placed into a box in such a way, that it will lie close to the wall *c* in front, so it cannot pass through the slot *d*. During the travel of the band *a*, each molding of a certain length will hit against a certain cam *g*. At first the longest moldings will be engaged by cam *g*, as shown in Fig. 1; later on the moldings of medium length by cam *g₂* and finally the shortest moldings by cam *g₃*. In hitting against a cam the moldings will be lifted from the front wall *c* of the box and tilted against the back wall *f*, of the box, from which it will slide down through the slot *d*.

Figs. 2 and 3 illustrate the arrangement of the boxes *b* of suitably constructed longitudinal shape, which are closed by bottom flaps *h* and which are kept in closed position under the influence of counter weights, springs or similar devices. The cams *g* are rigidly connected to the contact-pieces *k*, which are connected to an electric circuit of electro-magnets *l*. The cores *m* of the latter will be attracted, when the circuit is closed and moved from the position of Fig. 2 into the position of Fig. 3 into the path of the coun-

ter-weights *i*. By this means the flaps *h* of the boxes *b*, are opened (Fig. 3).

The closing of the circuit will be effected by means of the contact-pieces *k* whenever a molding touches a cam *g*. After being relieved through the cams *m*, the bottom flaps *h* will return to their closed position.

The opening of the closing flaps may be arranged in the same way, either entirely mechanically by means of lever-transmission and similar devices or by pneumatic or hydraulic designs. In any way must attention be paid, that the action of the key upon the cam will take place in a quick and sure manner.

The arrangement according to the invention does not necessarily need to include boxes of the described shape. Stop-devices will be sufficient, which, as an example may clamp the molding, whereby the clamping parts in touching the key parts, will release the moldings.

According to Fig. 4 an extension *n* of any shape and make is placed upon the molding *e*, in a hopper-like box, moved by an endless band *a*. When the extension *n* engages the cam *g* the molding will be tilted over from the vertical position into the inclined one and drop out through the bottom-opening of the hopper. It is possible in this way to deliver moldings without regard to their dimensions at a defined place.

It will be clear, that the assorting and delivering of moldings or similar material of any dimensions may be arranged according to the invention in the most simple and cheapest manner.

What I claim is:

1. A molding assorting apparatus, comprising a travelling conveyor, a series of molding-receiving receptacles carried by and movable with said conveyor, said receptacles having discharge openings at their lower ends and adapted to support moldings with portions of the latter projecting beyond the receptacles, and a series of gage bars projecting into the path of the moldings and adapted to position the latter in the receptacles for discharge through the said discharge openings.

2. A molding assorting apparatus, comprising a travelling conveyor, a series of molding-receiving receptacles carried by and movable with said conveyor, said receptacles having discharge openings at their

lower ends and adapted to support moldings in a substantially upright position with portions of the moldings projecting beyond the upper ends of the receptacles, and a 5 series of gage bars graduated in size projecting into the path of the moldings and adapted to position the latter in the receptacles for discharge through the said discharge openings.

10 3. A molding assorting apparatus, comprising a travelling conveyor, a series of molding-receiving receptacles carried by and movable with said conveyor, each of said receptacles being substantially in the 15 shape of an inverted triangle with a molding discharge opening in one wall near the apex of the triangle, and a series of gage bars projecting towards the receptacles and adapted to contact with moldings in said receptacles to cant the moldings and position 20

them for discharge through the said discharge openings.

4. A molding assorting apparatus comprising a travelling conveyor, a series of molding-receiving receptacles carried by 25 and movable with said conveyor, said receptacles having discharge openings at their lower ends and adapted to support moldings with portions of the latter projecting beyond the upper portions of the receptacles, extensions removably connected to the projecting portions of the moldings, and a series of fixed gage bars projecting into the path of the extensions to engage the latter and position the moldings in the receptacles 30 for discharge through the said discharge openings.

In testimony whereof I hereunto affix my signature.

DR. HANS SCHEIDEMANDEL.
